CARRY SET MECHANISM FOR CALCULATING MACHINES

Original Filed Nov. 23, 1920 2 Sheets-Sheet 2

Patented July 17, 1923.

UNITED STATES PATENT OFFICE.

EDWIN F. BRITTON, JR., OF MAPLEWOOD, NEW JERSEY, ASSIGNOR TO MONROE CALCULATING MACHINE COMPANY, OF NEW YORK, N. Y., A CORPORATION OF NEW YORK.

CARRY-SET MECHANISM FOR CALCULATING MACHINES.

Original application filed November 23, 1920, Serial No. 426,043. Divided and this application filed September 2, 1921. Serial No. 497,863.

To all whom it may concern:

Be it known that I, EDWIN F. BRITTON, Jr., a citizen of the United States of America, resident of Maplewood, in the county of Essex and State of New Jersey, have made a certain new and useful invention in Carry-Set Mechanism for Calculating Machines; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a plan view of a calculating machine embodying the invention.

Figure 2 is a section on the line 2—2, Figure 1.

Figure 3 is an enlarged detail side view of the pivoted carry-set member, with adjacent parts of the machine.

Figure 4 is a detail plan view of the carry-set member and its spring.

Figure 5 is a detail fragmentary view of the pivoted cam tooth.

The invention has relation to carry setting mechanism for use in calculating machines employing a delayed carry of the tens, having for its object the provision of means for this purpose which may be adjusted with a minimum of friction, while retaining complete accuracy of operation.

The invention consists in the novel construction and combinations of parts, as hereinafter set forth.

The accompanying drawings illustrate the invention as applied to a machine built in accordance with the disclosure of my co-pending application Serial No. 426,043, of which the present application is a division.

In these drawings the numeral 3 represents an operating crank handle, adapted to communicate motion to a train of equivalent gears 76, 75 and 74. Upon the shaft and fast with gear 75 is a smaller gear 80, meshing with a similar gear 81 mounted rigidly upon the shaft 4 of the selecting or primary gears 5. These gears 5 are arranged in sets of two, each set selectively positioned by a series of digital keys and connecting rock

bars, as explained in the reissue patent to Baldwin, No. 13,841, the teeth of each set being arranged in approximately a half-circle, so that the gears 5 may mesh with intermediate gears 12 during approximately a half-rotation of shaft 4, the other half rotation of said shaft being idle. The gears 12 mesh with and operate the gears of the numeral wheels 18.

Gear 74 is fast upon shaft 73, to which annuli *m* are also rigidly attached, these annuli serving to support laterally movable carrying teeth *j*, arranged in two oppositely pitched spirals each extending approximately one-fourth around shaft 73, a tooth of each spiral series being adapted to engage its respective intermediate gear 12.

Approximately the first quarter rotation of shaft 73 serves to carry one series of carrying teeth *j* idly past the gears 12, and corresponds to a portion of the idle movement of shaft 4. The next half-rotation of shaft 73 is also idle, and corresponds to the active or setting-up movement of shaft 4. The final quarter rotation of shaft 73 brings the teeth *j* of the second series successively into position to act upon the intermediate gears 12, in case of lateral positioning of the teeth *j* by their carrying cams 21; this movement of shaft 73 corresponding to the remaining idle movement of shaft 4, completing the cycle.

Reverse or subtractive rotation of the operating handle 3 will result in the same sequence of movements described for forward or additive rotation, except that the said first or idle series of carrying teeth *j* will now operate, and the second or other series will not act.

Pivotal carry-setting arms 14, having carry cams 21, are employed, each arm being provided with a cam extension 16, forming part of a pivoted tooth or element 16^a, pivoted at 16^b to said arm. Pins *q* of the numeral wheels engage the teeth 16^a as said wheels pass forwardly to or reversely from zero registering position, to actuate the arms 14 pivotally, the pivotal movement of said teeth being limited in each direction by contact of a stop wall 16^c thereof with the top of said arm, but being sufficient to pre-

vent incorrect carry operation by excess movement or over-rotation of the numeral wheels under momentum. This pivotal movement of an arm 14 serves to bring its 5 carry cam 21 into the path of movement of a tooth *j*, whereby said tooth will be moved laterally into position to engage and actuate the gear 12 of higher order.

- During subtractive or reverse rotation of 10 the parts, a roller *t* upon the annulus *m* engages one wall of a double cam extension *t'* of any arm 14 which may have been depressed, to restore the arm to normal position after the tooth *j* has acted; while during 15 additive or forward rotation the tooth *j* itself engages the opposite wall of cam extension *t'* after said tooth has been acted upon by cam 21, and will restore the arm 14 to normal position.
- 20 The teeth 16 have a movement approximately radial of the numeral wheels in the pivotal movement of the arms 14, so that the camming action of the pins *q* will be similar in forward or reverse rotation of the numeral wheels. The carry cams 21 lie in a plane radial of the pivot shaft 15, and in operative position will be substantially tangent to the path of movement of the teeth *j*, in order that the thrust of the teeth *j* upon either cam surface of the member 21 may be resisted by said shaft and no tendency to displacement of the arm 14 occur. In order to attain these relations of movement and position in the limited space between the wheels 13, the intermediate gear shaft 11 and the carry teeth *j*, the shafts 60, 11, 73 and 15 are placed in quadrangular relation, the shafts 11 and 15 thus lying upon opposite sides of a plane intersecting 30 the shafts 60 and 73.

For the purpose of holding the pivotal arms 14 yieldably in either position of adjustment, U-form springs 18 have respectively one arm thereof pivotally engaging in permanent fixed manner a seat 17 of the shaft 11 and the other arm thereof pivotally engaging in permanent manner a seat 19 of the related arm 14, the latter in its movement from one angular position 45 of adjustment to the other moving the spring and the seat 19 into and past alignment with the arm 14, the seat 17 and the shaft 15, and thereby compressing the arms of said spring and tensioning the same, the 50 thrust of the spring aiding to complete the movement of the arm 14 and the latter being adapted to contact with the shaft 11 to limit the movement in either direction. In the movement of the arm 14 from 55 one angular position of adjustment to the other, the spring 18, which in its first position is angularly related to the arm 14 at one side of a line connecting the center of shaft 15 with the seat 19, is moved to another angularly related position with said

arm at the other side of said line. It is therefore obvious that the spring 18 will in either angular position of adjustment resist movement of the arm 14.

I claim:

1. In a calculating machine, numeral wheels rotatable in either of two directions, carry mechanism including driving elements, and reciprocatory pivoted arms operable by said numeral wheels and adapted 70 to move said elements from inactive to active position, said arms having each a pivoted tooth engaged by said wheels and being thereby adapted to allow excess movement of said numeral wheels when suddenly checked without depression of the arms.

2. In a calculating machine, numeral wheels rotatable in either of two directions, and carry mechanism similarly rotatable and including rotary driving elements and reciprocatory pivoted arms operable by said 75 numeral wheels and adapted to move said elements from inactive to active position, said arms having each a double-beveled pivoted tooth having a limited movement pivotally in either direction and operable by the numeral wheel at the end of the movement of the tooth in either direction, said arms being thereby adapted to allow excess movement of the numeral wheels in either 80 direction when suddenly checked without depression of the arms.

3. In a calculating machine, numeral wheels, carry mechanism including driving elements, members pivotally operable by the 85 numeral wheels to render said elements operative, and springs having permanent seats in said members and permanent fixed seats and serving to hold said members in either of two angular positions.

4. In a calculating machine, numeral wheels, carry mechanism including driving elements, reciprocatory members pivotally operable by the numeral wheels to render 90 said elements operative, and U-form springs 95 having each an arm permanently engaging a seat in the related member and an arm permanently engaging a fixed seat and movable by the pivoted member past the point of greatest compression, to hold said member in either of two angular positions.

5. In a calculating machine, numeral wheels, carry mechanism including driving elements, reciprocatory pivoted members movable by said numeral wheels into the 100 path of said driving elements, and means for holding the pivoted members in either 105 position, including springs adapted each to assume two angular positions and to be moved through an aligned position relative 110 to its respective member and to be tensioned 115 in its movement into line.

6. In a calculating machine, numeral wheels, carry mechanism including driving elements, reciprocatory pivoted members 120

movable by said numeral wheels into the path of said driving elements, and means for holding the pivoted members in either position, including pivotally mounted springs having pivotal engagement with said members and adapted each to assume two angular positions and to be moved through an aligned position relative to its respective

member and to be tensioned in its movement into line

In testimony whereof I affix my signature in presence of two witnesses

EDWIN F. BRITTON, JR.
